UNITED STATES PATENT OFFICE

EUGENE PLATZNER, OF CLEVELAND, OHIO

DESIGN FOR A GARMENT

Application filed February 23, 1933. Serial No. 47,300. Term of patent 3½ years.

To all whom it may concern:

Be it known that I, EUGENE PLATZNER, a citizen of the United States of America, residing at 2882 Detroit Avenue, Cleveland, Ohio, have invented a new, original, and ornamental Design for a Garment, of which the following description in connection with the accompanying drawing, is a specification.

The figure is a front view of the garment showing my new design. The back of the garment is substantially unornamented.

I claim:

The ornamental design for a garment, substantially as shown and described.

EUGENE PLATZNER.
